CLAIM

The ornamental design for a spacer for concrete reinforcement wire, as shown and described.

DESCRIPTION

FIG. 1 is a perspective view of the present invention.

FIG. 2 is a left side view thereof.

FIG. 3 is a right side view thereof.

FIG. 4 is a backside view thereof.

FIG. 5 is a front side view thereof.

FIG. 6 is a top view thereof.

FIG. 7 is a bottom view thereof.

FIG. 8 is a perspective view of another embodiment of the present invention.

FIG. 9 is a right side view thereof.

FIG. 10 is a left side view thereof.

FIG. 11 is a front view thereof.

FIG. 12 is a rear view thereof.

FIG. 13 is a bottom view thereof; and,

FIG. 14 is a top view thereof.

The broken lines represent portions of the design that form no part of the claim.
